SUPPORT FOR A DIVING BOARD

Myron P. Anthony, South Gate, Calif., assignor to Anthony Pools Inc., South Gate, Calif., a corporation of Delaware

Filed Apr. 27, 1962, Ser. No. 69,878

Term of patent 14 years

(Cl. D13—1)

FIGURE 1 is a perspective view of a support for a diving board embodying my new design; and

FIGURES 2, 3 and 4 are top, side elevational and front elevational views, respectively, thereof.

I claim:

The ornamental design for a support for a diving board, as shown.
